WARP STOP MOTION

Application filed June 20, 1930. Serial No. 462,674.

This invention relates to warp stop motions either of the mechanical or electrical type, and it is the general object of the invention to facilitate the assembly of motions employing several similar units which may be built up to provide a stop motion having any desired number of banks of drop wires.

In the form of motion to which my invention more particularly relates there is a horizontal supporting member on which is strung several substantially similar but separate units so related that the drop wire separator bars and also the detecting bars may be held between the units in properly spaced relation. Although the invention is illustrated herein in connection with an electrical motion, yet the invention is not limited to electrical apparatus.

In assembling a motion of this type the operator is required to handle a detector and also a separator bar for each unit, and it is an important object of the invention to provide supporting means for one of these elements while the other is being manipulated by the user. More specifically, it is an object of the invention to provide each of the separator units with a finger or the like effective to support the separator bar when adjacent units are separated sufficiently to permit insertion of the detector bar.

It is a further object of the invention to relate the parts in such a way that the finger which supports the separator bar may also serve to align the units and keep them from turning with respect to each other and the supporting member during the assembling operation.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a vertical section through a warp stop motion made according to my invention, a part of one of the separator units being broken away to illustrate the invention more clearly,

Fig. 2 is a plan view of the structure shown in Fig. 1,

Fig. 3 is a vertical section along line 3—3 looking in the direction of the arrows, Fig. 1,

Fig. 4 is a vertical section looking in the direction of arrows 4—4, Fig. 1, and

Fig. 5 is a diagrammatic view showing the manner in which my invention operates when the motion is being assembled.

Referring to the drawings, the loom frame 10 supports a bracket 11 in which is mounted for vertical adjustment a post 12. The latter has supporting relation with respect to a horizontal screw 13 which extends substantially parallel to the warp threads W and may lie close to the adjacent loomside. There is shown in the present drawings a structure on one side of the warp threads only, but it is to be understood that the cross members, such as the detector and separator bars, will be supported at each side of the warp threads by a structure substantially as set forth herein.

Mounted on the screw 13 is a plurality of separator units 14 each having vertical surfaces 15 which lie opposite corresponding surfaces 16 on the adjacent unit. The outside electrode 17 of an electric contact bar is located between these surfaces 15 and 16 and is held frictionally by them in fixed position. Each unit is provided with a notch or groove

18 having a lower edge 19 on which the separator bar 20 may rest, and the notch has a vertical surface 21 opposite a surface 22 on the adjacent unit, said surfaces clamping the separator bar in position. An end holder 23 may be interposed between the outside nut 24 and the nearest unit 14, and the unit at the opposite end of the motion, or that at the right as shown in Fig. 1, may be positioned by a nut 25. The separators are spaced so as to define compartments or guideways for banks of drop wires D, and the latter have slots S through which the contact or detector bar 17 extends.

The matter thus far described forms no part of my present invention and may be adapted to take mechanical forms of detector bars as well as the electrical form set forth herein.

In carrying my invention into effect I pro-

vide the lower portion of each of the units and also the holder 23 with a pocket 30 into which extends a finger 31 projecting from the adjacent unit 14. The finger may be slightly less than the width of the pocket, as shown in Fig. 4, but will nevertheless act as a guide so that when one of said units is in place the next one to be added will be positioned by the tongue of the first and held thereby against substantial angular displacement around the screw 13.

Fig. 5 shows diagrammatically how the tongue facilitates assembly. It is assumed that the right hand unit is in proper position and that its separator bar 20 is supported on the lower surface 19 and also the finger 31. The left hand unit is spaced sufficiently on the first one to permit the contact bar 17 to be moved downwardly as shown, but it will be noted that the finger 31 is close enough to the left unit so as to support the separator bar even though the latter should slide down from the inclined position shown. In this way it is possible for the operator to hold the separator bar between two units which are spaced sufficiently to permit insertion of the detector bar.

It is to be understood that before the units 14 are locked together they are freely rotatable about screw 13, so that when a unit is in the position shown at the left of Fig. 5 it may be given a slight angular displacement to bring the finger 31 opposite a solid portion of the left unit adjacent the pocket 30, such as indicated in 32 in Fig. 3, thereby holding the units spaced to permit entry of the detector bar.

From the foregoing it will be seen that I have provided a simple device for facilitating assembly of a warp stop motion made on the unit principle, the construction permitting placement of the separator bar in a pocket which will retain it and then adding the detector bar. Adjacent units may be displaced angularly a slight amount, and when so positioned, the operator may press the left unit against the one already in place without being careful to maintain its spacing and still be able to put the detector bar in place. After the latter is in position the left hand unit may then be turned to cause the finger to register with the pocket, after which the parts may be drawn together. Also, the finger 31 acts to prevent relative angular displacement of two adjacent units.

Having thus described my invention it will be seen that changes and modifications may be made therein by those skilled in the art without departing from the spirit and scope of the invention and I do not wish to be limited to the details herein disclosed, but what I claim is:

1. In a warp stop motion, a plurality of substantially similar units arranged one adjacent the other, a holder for the units, a de-

tector bar lying between two adjacent units, a separator bar lying between said two units, and means supported by the holder to support the separator bar in position between the units when the elements are spaced apart a distance equal at least to the horizontal dimension of the detector bar.

2. In a warp stop motion, a plurality of substantially similar units arranged one adjacent the other, a detector element lying between two adjacent units, a separator bar lying between said two units, and means carried by one of the units to support the separator bar in position between the units when the elements are spaced apart a distance equal at least to the horizontal dimension of the detector bar.

3. In a warp stop motion, a plurality of substantially similar units arranged one adjacent the other, a detector element lying between two adjacent units, a separator bar lying between said two units, and means on one unit normally overlapping the other to support the separator bar in position between the units when the elements are spaced apart a distance equal at least to the horizontal dimension of the detector bar.

4. In a warp stop motion, a series of juxtaposed substantially similar units, adjacent units being formed with means defining an upper pocket, a detector member to enter said upper pocket, adjacent units having other surfaces defining a second pocket, a separator bar in the second pocket, and means to retain the separator bar in said second pocket when the units are spaced sufficiently to afford entry of the detector bar in the first named pocket.

5. In a warp stop motion, a series of juxtaposed substantially similar units, adjacent units being formed with means defining an upper pocket, a detector member to enter said upper pocket, adjacent units having other surfaces defining a second pocket, a separator bar in the second pocket, and means on one unit normally overlapping the other to retain the separator bar in said second pocket when the units are spaced sufficiently to afford entry of the detector bar in the first named pocket.

6. In a warp stop motion, a plurality of juxtaposed substantially similar units, a holder for the units, a detector bar, a separator bar, adjacent units having provision for clamping between them a detector bar and a separator bar, said units being separable to afford opportunity to place the bars in position, and means supported by the holder to support one of said bars in position between the units when the units are spaced sufficiently to afford entry of the other bar between said units.

7. In a warp stop motion, a substantially horizontal support, a plurality of substantially similar units strung along the sup-

port, a separator bar located between adjacent units, a detector bar located between said units, one of said units having a pocket, and a finger formed on the other unit to enter the 5 pocket, said finger being located under the separator bar to have supporting relation with respect thereto when the units are spaced sufficiently to position the detector bar.

8. In a warp stop motion, a substantially 10 horizontal support, a plurality of substantially similar units strung along the support, a detector bar, adjacent units having adjacent surfaces to be spaced to permit the detector bar to be moved to position, a separator 15 bar located between the units, said units having overlapping portions so proportioned that when the said surfaces of the units are spaced apart a distance exceeding the horizontal dimension of the detector rod said 20 overlapping portions will have supporting relation with respect to the separator bar.

9. A claim according to the structure set 25 forth in claim 7 wherein the support is cylindrical and the units are movable angularly therearound, each unit having a portion adjacent its pocket to engage the units of the adjacent finger and hold the units in spaced relation.

In testimony whereof I have hereunto aff- 30 fixed my signature.

JOHN G. AHLIN.
